PAINT BUCKET LADDER BRACKET

Joseph C. Dodd, Orlando, Fla.

Application December 7, 1945, Serial No. 633,308

4 Claims. (Cl. 248—210)

1

This invention relates to a paint bucket bracket or support designed for use with ladders, an important object being to provide a support of this character which will support a paint bucket in an upright position on a leaning ladder, thereby preventing waste of the paint caused by handling or moving the ladder when the paint bucket is full or substantially full of paint.

Another object of the invention is to provide a support of this character for supporting paint buckets which will hold the paint bucket supported therein, rigid, with respect to the ladder, so that the painter will have ready access to the paint in the bucket.

Still another object of the invention is to provide a support which will not swing when positioned on a ladder, and one which may be used at either side of the ladder, for the convenience of the painter using the device.

With the foregoing and other objects in view which will appear as the description proceeds, the invention consists of certain novel details of construction and combinations of parts, herein-after more fully described and pointed out in the claims, it being understood that changes may be made in the construction and arrangement of parts without departing from the spirit of the invention as claimed.

Referring to the drawing:

Figure 1 is an elevational view of a paint bucket support for use with ladders, constructed in accordance with the invention.

Figure 2 is a plan view thereof illustrating the support as positioned on a ladder.

Figure 3 is a front elevational view of the support.

Referring to the drawing in detail, the device comprises a body portion including the lower section 5 and upper rear section 6, the sections 5 and 6 being constructed of sheet metal material bent to provide side flanges 7 and 8 respectively, the flanges 7 and 8 of each section being parallel and spaced apart a distance to permit the flanges to be positioned over the side bar of a ladder. The flanges 8 of the rear section 6 extend between the flanges 7 of the lower section 5, where they are riveted to the flanges 7 by means of rivets 9. The rear section 6 is disposed at an obtuse angle with respect to the upper surface of the lower section 5, so that when the support is positioned on a ladder which is leaning against a building or other surface, the upper surface of the lower section 5 will be substantially horizontal.

Elongated openings 10 extend inwardly and 55

2

upwardly from the rear edges of the flanges 8, the elongated openings being of widths to receive a rung of a ladder to secure the support in position.

5 Rising from the front end of the lower section 5 is a bar 11 which diverges towards its upper end providing a wide band engaging section which is riveted to the band 12 by means of rivets 13. Extending from the band are arms 14 that have right-angled ends 15 riveted to the rear section 6, by means of the rivets 16.

10 The location of the band 12 is such that a paint bucket positioned therein, will rest on the upper surface of the lower section 5 of the bracket, the band preventing displacement of the bucket held in the support.

15 In order that the device may be conveniently handled, a bail 17 is provided, the bail having its ends extending through openings in the band 12.

20 From the foregoing it will be seen that due to the construction shown and described, I have provided a paint bucket support which may be readily positioned over one of the side bars of a ladder at a point adjacent to one of the rungs of the ladder, where the elongated opening receives the rung. The support will be held against twisting, as well as downward movement due to this construction.

25 It might be further stated that with applicant's support, the paint bucket which contains the paint used by painters, will be so located that the painter will have easy access to the paint, to facilitate the painting operation.

30 What is claimed is:

1. A paint bucket support for ladders, comprising a lower section and a rear section extending upwardly at an obtuse angle with respect to the lower section, each section embodying spaced flanges adapted to fit over the side bar of a ladder, the flanges of the rear section having elongated openings extending inwardly from one edge thereof, said openings adapted to accommodate a rung of a ladder, and a band secured to the support in spaced relation with the lower section, in which a paint bucket is positioned.

2. A paint bucket support for ladders, comprising a lower section and a rear section, spaced flanges formed on the sections, said spaced flanges adapted to fit over the side bar of a ladder, means for securing the support against movement longitudinally of the ladder, a band secured to the support in spaced relation with the lower section and within which a paint bucket is posi-

tioned, the paint bucket resting on the lower section, and a bail secured to the band.

3. A paint bucket support for ladders, comprising a lower section and a rear section secured to the lower section, the rear section being disposed at an obtuse angle with respect to the lower section, said support adapted to be positioned on a side bar of a ladder, said support having elongated openings extending inwardly and upwardly from one edge thereof and adapted to accommodate a rung of a ladder, a band secured to the rear section and over-lying the upper surface of the lower section in spaced relation therewith, said band and upper surface of

the lower section providing a support for a paint bucket positioned within the band.

4. A paint bucket support for ladders, comprising a lower section and a rear section, said sections embodying spaced flanges, the flanges of the rear section being disposed between the flanges of the lower section and secured thereto, a band secured to the rear section, an arm extending upwardly from the free end of the lower section, said arm being connected to the band supporting the forward portion of the band, and means for securing the support in position on a ladder.

JOSEPH C. DODD.
